(57) **CLAIM**

The ornamental design for a segmented flag having zipper and Velcro joining means, as shown and described.

DESCRIPTION

FIG. 1 is a front and side perspective view of a segmented flag having zipper and Velcro joining means, showing my new design in a partially opened state;

FIG. 2 is a front view thereof;

FIG. 3 is a rear view thereof shown in a closed state;

FIG. 4 is a front view thereof in a closed state; and,

FIG. 5 is an enlarged fragmentary side view thereof taken in the direction of the arrows upon the line 5—5 of FIG. 4.
